UNITED STATES PATENT OFFICE.

ANDREW REID AND JOHN JAMESON, OF AKENSHIDE HILL, NEWCASTLE-
UPON-TYNE, ENGLAND.

TRANSFORMATION PICTURE AND PRINT.

SPECIFICATION forming part of Letters Patent No. 356,695, dated January 25, 1887.

Application filed October 5, 1885. Serial No. 179,076. (No model.) Patented in England January 31, 1885, No. 1,380; in France March 7, 1885, No. 167,490, and in Belgium April 24, 1885, No. 68,631.

To all whom it may concern:

Be it known that we, ANDREW REID, printer, and JOHN JAMESON, consulting engineer, both subjects of the Queen of Great Britain and 5 Ireland, and both residing at Akenside Hill, Newcastle-upon-Tyne, England, have invented certain new and useful Improvements in Transformation Pictures and Prints, (for which we have applied for patents in Great Britain, No. 10 1,380, dated January 31, 1885, and have obtained patents in France, dated March 7, 1885, No. 167,490, and Belgium, dated April 24, 1885, No. 68,631,) of which the following is a specification.

15 Our invention consists in improvements in pictures and prints, so as that part of a picture or print shall be fixed to and part removable from the paper on which it is placed, and is a new application of the process of protected 20 cheque-printing patented by John Jameson, in Great Britain on December 27, 1883, No. 5,878.

In carrying out our invention we proceed as follows: We print upon ordinary paper or 25 card any convenient design, which we call "the fixed design," and then coat the whole or part of the paper so printed with such material as starch and gum, so as to form upon it a soluble invisible, or scarcely visible, medium; and when this coating is dried we print 30 upon it, in register with the print of the fixed design, a superimposed design either covering entirely the fixed print or partially covering it, and forming with uncovered portions of the 35 fixed design a complete picture. The effect of this arrangement is that if the print is washed with a solvent of the film the design will be transformed by the removal and disappearance of all parts of the print which are placed 40 above the couch of soluble medium, and the fixed design only will appear. As an alternative, we may use for the first printing ordinary printing-ink, and for the second printing a soluble ink composed of such material as 45 gum and glycerine, or soap or albumen, and treacle, with coloring-matter ground up as an ink, so that on the solution of the soluble ink the transformation is effected; and it is of course possible still further to vary the pro-

cess by using over the fixed print films or soluble inks, perhaps insoluble in water, but soluble in other material, or to use one fixed ink with one ink or film soluble in water and another ink or film soluble, for instance, in spirit, but not in water.

50 Our invention is applicable also to other printed matter as well as pictures, and the printing may be produced either in the ordinary printing-press or by the lithograph process, or otherwise, and may be extended so 55 that more than one printing (as in chromolithography) shall be fixed and more than one printing shall be deleble.

We purpose to use the invention for advertisements, and in Christmas-cards, birthday-cards, in valentines, and similar matters, and as a source of amusement and instruction for 60 children.

Having thus described the nature of our invention, we will proceed more particularly to 65 describe the manner in which the same is to be performed—that is to say:

Referring to the accompanying drawings, Figure I is a view representing the appearance of a picture having the fixed design, coating 75 on the fixed design, and superimposed removable design. Fig. II is a view showing the transformed appearance of the picture after the superimposed design has been washed off.

A is the paper or backing; B, the fixed design; C, the coating, and D the removable design.

In the process we prefer to use we make a 80 solution of gum-arabic in water so that the density of it is about 1.085 to 1.100, water being 85 1.000, and we add to it a strong solution of starch in such proportions (which must vary with the quality of the starch) as that when spread on paper A it shall dry without a disagreeable glaze. This we employ for the soluble film C, before mentioned. Next, unless the paper be specially prepared in the mill, we wet the paper to be used for printing, and allow it to dry again, so as to take out the stretch which paper gets usually in the mill, 90 and we prefer to allow it to dry each sheet by itself, so that its contraction may be uninhibited. When it is dry, we print it the first 95

time, and when the print B has dried we coat the paper, either with a brush by hand or in a varnishing machine, with the film composition C, before described, and again allow it to dry, 5 each sheet by itself. We then press in considerable quantity the sheets together, so as to make them flat and convenient for the second print, D, and then apply in register with the first the second printing in the ordinary way, and 10 when this is dry, if there be several in a sheet, we cut into separate pictures. If the exact 15 register of the two prints is not of much importance, we omit the first wetting of the paper, and we sometimes omit it if the picture is small and not many printed on the same sheet. The object of the first wetting is to prevent the difficulty of register from distortion of the sheets of paper by shrinkage in the 20 drying of the film. When a soluble ink is used for the second printing and no coating of film is applied, we omit the wetting of the paper.

The thickness of coat of film should vary with the absorptive power of the paper. A hard paper will require less and a soft paper 25 more; and it also depends to some extent upon the depth of shading of the top print. It is impossible to lay down specific rules to suit the various circumstances, excepting that a sufficient coating must be applied to prevent 30 penetration of the ink of the top print.

Although we have described the material of the soluble film which we prefer to use, we do not confine ourselves to that material, as other materials are if not equally good at least nearly 35 so. For instance, dextrine may be substituted for the gum, and ordinary paste may be substituted for both the starch and gum, and there are many other substances which may be used in the same manner. Although, also, we 40 have described the application of the film by a brush or varnishing machine and as if it was over the whole of the paper, we sometimes coat only parts of the paper to be printed, and we may carry this out by the application of 45 the soluble film as a print with a light pressure from a soft-wood block, (such as a pear tree;) or we may print the soluble film from the wood block as last described in the form

of a more or less minute invisible design, and either before the first printing of the paper or 50 after, so that only the parts of the visible print which are over the invisible print are removed by sponging.

It will be clear that all printing in ordinary printing-ink over a soluble film, and whether 55 in one color or more, is delible, and all printing in ordinary printing-ink direct upon the paper, whether in one color or more, is fixed to the usual extent.

We claim—

1. A transformation picture or print consisting of a backing having an indelible imprint thereon and a deleble print upon said imprint and backing concealing in whole or in part the imprint, substantially as described. 65

2. A transformation picture or print consisting of an indelible imprint and two or more separate printings superimposed in films soluble in different media, so as on application of the solvents of the films to develop transformations, substantially as described. 70

3. A transformation picture or print consisting of a backing or sheet, a fixed design or imprint on the backing or sheet, and a removable design or printing concealing in whole 75 or in part the fixed design or imprint and adapted to be washed off without destroying the latter.

4. A transformation picture or print consisting of a backing or sheet, a fixed design or 80 imprint on the backing or sheet, a coating on said fixed design or imprint, and a removable design or printing over the fixed design or imprint concealing the latter in whole or in part, substantially as described. 85

In testimony whereof we have signed our names to this specification in the presence of two subscribing witnesses.

ANDREW REID.
JOHN JAMESON.
